UNITED STATES PATENT OFFICE.

WILLIAM F. MAHONY, OF WASHINGTON, DISTRICT OF COLUMBIA, ASSIGNOR
OF ONE-THIRD TO CHARLES H. RIDENOUR, OF SAME PLACE.

DESIGN FOR AN EYE-SHADE.

SPECIFICATION forming part of Design No. 33,245, dated September 25, 1900.

Application filed November 23, 1899. Serial No. 738,112. Term of patent 7 years.

To all whom it may concern:

Be it known that I, WILLIAM F. MAHONY, a citizen of the United States, residing at Washington, in the District of Columbia, have invented and produced a new and original Design for Eye-Shades; and I do hereby declare the following to be a full, clear, and exact description of the invention, such as will enable others skilled in the art to which it applies to make and use the same.

In the drawings, Figure 1 is a plan view of my eye-shade. Fig. 2 is a section on line 2, Fig. 1.

As shown in the drawings, the shade consists of a broad flat full portion A, the outer periphery of which is formed by an arc of a circle and the inner portion of which is formed by an arc of a circle of a longer radius than that of the outer portion, and these two cir-

cles gradually approach each other at the rear of the shade and extend backwardly, so as to present narrow elongated tongues. The ends of the tongues are joined by a straight cross-piece, and the shade, including the cross-piece, is perfectly flat and even, presenting a substantially-plain surface on both sides.

What I claim, and desire to secure by Letters Patent, is—

The design for an eye-shade substantially as herein shown and described.

In testimony whereof I affix my signature in the presence of two witnesses.

WILLIAM F. MAHONY.
